UNITED STATES PATENT OFFICE.

FREDERICK BRACKETT, OF WASHINGTON, DISTRICT OF COLUMBIA.

SLEEPING-CAR.

1,048,131.

Specification of Letters Patent.

Patented Dec. 24, 1912.

Application filed October 5, 1910. Serial No. 585,530.

To all whom it may concern:

Be it known that I, FREDERICK BRACKETT, a citizen of the United States, residing at Washington, in the District of Columbia, have invented new and useful Improvements in Sleeping-Cars, of which the following is a specification.

The objects of my invention are varied. Among them the more important may be mentioned. I aim to obtain more room in the berths of sleeping cars, to eliminate the disadvantages of the upper berth, and to place it on an equal footing with the lower berths, to better ventilation, to secure more uniform and agreeable heating, to reduce the cinder deposits on seats, and to remove objectionable features of travel due to cinders, dirt and dust, to provide added conveniences for passengers, to increase the facility with which berths may be made and broken, to increase the efficiency of the sleeping car generally, to decrease its cost of manufacture, and to render the parts and mechanisms of the sleeping compartments more durable.

In the attainment of the objects of my invention, I divide a car having a housing of the usual form centrally by a longitudinal partition extending nearly to each end of the car, locate the seats on opposite sides of this partition with their ends abutting the partition, and provide an aisle on each side outside of the seats. It should at once be apparent that passengers will have the same view through the windows of the car across the aisle as they have with the seats immediately adjacent the windows, the interruption due to passage of people up and down the aisle being only slight. Further it should be apparent that due to the removal of the seats from the immediate proximity of the windows, dust, dirt, and cinders blowing in through the windows, will fall for the most part in the aisle, and will not deposit on the seats and inconvenience the passengers to such degree as is at present the case.

Further I form a lower berth in each compartment by making the bed of the berth of two seats which face each other, and of a berth section adapted to fill the space normally present between the two seats the said additional section being associated with and

preferably housed when closed and not in use, against the central partition. Preferably this section is hinged at its bottom end at the level of the seats, and is adapted to be lowered or swung outwardly from the partition to its place between the two facing seats.

The upper berth I form by raising the backs of the two facing seats comprised in the lower berth to a horizontal plane at the height of the upper ends of the backs in normal position. Preferably these backs are hinged at their upper edges and are adapted to be swung upwardly and outwardly into the plane of the bed of the upper berth. A filling section, similar to the filling section of the lower berth, is associated with the partition above the section of the lower berth, and, in a similar manner by making the backs of the seats of a suitable height all the space now available in lower berths may be secured in this arrangement and more, while in the upper berths owing to the central location of the berths considerable additional space is available owing to the raised roofs of cars. Sufficient space is readily had by this arrangement to enable a person of average height to stand in the upper berth.

In both the upper and lower berths I provide suitable lockers and racks for the reception of clothing and personal articles, and in the upper berth I provide two drop seats associated with the central partition or dividing wall and adapted to be supported by the wall in position to be used by the occupant above at will, and to be readily stored away when desired.

Still further in the attainment of the objects of my invention I make the central partition or wall of sufficient thickness to give space for lockers in its interior, and so dimension these lockers and so form the doors therefor that the doors may be swung outwardly to form compartment partitions immediately above the skeleton backs of the seats which form compartment partitions between the lower berths.

The arrangement of the berths with respect to the roofing of the car and with respect to the heating system is such that excellent ventilation and heating is secured,

and that the comfort of passengers is greatly increased.

In the accompanying drawings I show one embodiment of my invention, which embodiment is the best form of my invention now known to me, but it will be evident upon an understanding of this embodiment, that my invention may be given other forms without departing from its generic spirit.

Of the drawings—Figure 1 is a perspective view of the compartment of the sleeping car of my invention with the seats in their normal condition, that is with the berths broken; Fig. 2 is a perspective view of the same compartment showing the berths made, and the compartment partitions in position; Fig. 3 is a transverse section of a sleeping car taken centrally through the opposed compartments, showing the berths in position for use and the seats dropped down; Fig. 4 is a plan view of the car of my invention with the roof removed to show the interior arrangement of the seats; Fig. 5 is a detail of an upper berth step.

Referring first to Figs. 1, 2 and 3 of the drawings, 10 designates the main body of the housing of the car which is provided with a centrally raised roof portion 11. This housing is divided centrally for a suitable distance by a partition or wall 12 of considerable thickness, the partition having at each side a double wall formed by boarding 13 and 14 spaced apart. Seats 15 and 16 are arranged in the usual manner facing each other and transversely of the car on opposite sides of this partition, with one end abutting the partition and with the other end on an aisle 16* between these other ends of the seats and the side of the car. Thus the car is divided into two halves, over each half of which a conductor has an unobstructed vision when the seats are in their normal condition for day traveling as shown in Fig. 1. The seats being removed from the windows prevents the ready access of cinders, dust and dirt to them, and at the same time gives the passengers the same view of the windows as would be had if the seats were placed abutting the side walls of the car.

Hinged centrally of each compartment on partition 12 is a section 17, hinged by hinges 20 at its lower end and on its inner edge, so that its body is against the partition as shown in Fig. 1, and so that it lies parallel to the face of said partition when it is raised. This section is of the same length as the seats and is adapted to be lowered to a position between them as shown in Fig. 2, and to complete the bed of the lower berth. The space previously occupied by it may when it is laid down be used for storing clothing, and other articles of

apparel. The backs 18 of these seats are 65 hinged at their upper ends in such a manner that they may be turned upwardly to position shown in Fig. 2 by simply moving the cushions 15 and 16 of the seats to release their lower ends. They may be positioned 70 in horizontal plane at the normal height of the backs of the seats as shown in Fig. 2. Immediately above the section 17 which completes the bed of the lower berth is a similar but narrower section 19 which is 75 hinged at one end against the outer boarding 14, and adapted, when not in use, to swing upwardly against the boarding 14. This section 19 is of a width sufficient to completely fill in the space between the 80 lower edges of the backs 18 when the latter are raised into a horizontal plane to complete the upper berth. The opening in the boarding 14, as best seen in Fig. 3, which registers with the section 19 receives bedding and the like carried on the section 19 when the latter is raised up out of the way, the compartment behind the boarding 14 housing the bedding. Any desired and suitable fastening means may be provided for 90 retaining the sections 17 and 19 upright in the partitions, as for instance the locks 19* indicated by outline in Fig. 1. Pins 21 in the seats 15 and 16, and in the lower ends of their backs 18, are adapted to enter holes 95 21 in the sections 17 and 19 to hold their outer ends in place. By making the backs of the berths of sufficient height, the space between the lower and upper berths may be made anything desired. It will be observed 100 that the seats terminate substantially under the beginning of the rise in the roof, and that there is therefore quite a space available in the upper berth by virtue of the location of the berths beneath the rise 105 11. This space is such as to enable a person of ordinary height to stand within the berth.

The mattresses are stored within lockers 22 in the space between the walls 13 and 14 110 of the partition 12. The doors 23 of these lockers are hinged at the corners of the compartment, and are adapted to swing outwardly to the position shown in Fig. 2 and constitute compartment partitions between 115 the upper berths in the same manner as the skeleton backs 24 constitute compartment partitions between the lower berths. When the mattresses are removed the space which they occupied is available for storing clothing, and I provide suitable hooks within the lockers in each case for this purpose. Further I provide seats 25 movable toward and from the boarding 13, and in this instance hinged to the boarding 13 at one end in such 120 a manner that they may be swung outwardly as shown in Fig. 2. Their outer ends may be supported by cords 26 or by other means.

Above the aisles and in the angles between the sides and the roof, are provided racks 27 for the receipt of articles from the upper berth. Lockers 28 are also provided in the 5 upper compartments above the folding sections 19 for the convenient use of passengers, these lockers 28 being secured against the boarding 14.

The curtain usually used is mounted on a 10 pole 29 supported immediately below the racks 27, and serves its usual functions. Steps 30 and 31, hinged to the sides of the seat posts 32 of the seats, and adapted to automatically swing upwardly and out of 15 the way when not in use are provided for convenient reaching of the upper berth. As shown a simple spiral spring in connection with a hinge secures the steps in their folded position. (See Fig. 5.)

20 That the ventilation of this car will be excellent will be readily understood when it is considered that the upper side lights 33 may be readily manipulated by the porter, and that circulation of air takes place through 25 these and through the bottom gratings 34 in the floor of the car. The heating apparatus 35 is located in its usual place on the sides of the car, and the rising heated air will pass into both berths, and passing 30 through the racks 27 will escape through the side lights 33.

That I have obtained the objects of my invention and that I have further produced a sleeping car in which the parts may be 35 made with great facility and the parts of which are combined to secure the best efficiency should be apparent.

What I claim is:

1. In a sleeping car, a sleeping compartment comprising a wall, two seats arranged 40 facing each other at right angles to said wall and spaced apart, the backs of said seats being adapted to be raised to a horizontal plane to form a bed, a small bed section hinged against said wall and normally resting in a folded up position and adapted 45 to be lowered to fill the gap between the two raised backs of the seats, lockers in said wall on opposite sides of said bed section, 50 and doors for said lockers, the said doors being of dimensions adapting them for service as compartment partitions above the skeleton backs of the seats.

2. In a sleeping car, a sleeping compartment comprising a wall, two seats arranged 55 facing each other at right angles to said wall and spaced apart, the backs of said seats being adapted to be raised to a horizontal plane to form a bed, a small bed 60 section hinged near said wall and being normally folded up to a vertical position and adapted to be lowered to fill the gap between the two raised backs of the seats, lockers in said wall on opposite sides of said bed

section, and doors for said lockers hinged on 65 the sides adjacent the backs of the seats, and of a dimension adapting them for service as compartment partitions above the skeleton backs of the seats.

3. In a sleeping car a central partition, 70 boarding spaced from the side of the partition to provide a storage compartment, skeleton backs outstanding in parallel spaced relation from the partition, opposed seats arranged at the lower ends of the skeleton 75 backs, hinged backs mounted upon the upper ends of the skeleton backs and adapted to swing up into parallelism with the seats, a lower berth section hinged against the partition and adapted to join the seats to form 80 a lower berth, and an upper berth section hinged against the boarding and adapted to join the raised backs to form an upper berth.

4. In a sleeping car, a central partition, 85 boarding spaced from the side of the partition and providing a storage space and having a number of openings therethrough for the introduction of articles, panels hinged to the boarding and normally closing 90 the openings therein, opposed seats outstanding from the partition and having backs hinged at their upper ends and adapted to swing up into a horizontal plane, a section hinged against the partition be- 95 tween the seats and adapted to swing down and close the space between the seats to form a lower berth, and a second section hinged against the boarding and adapted to swing down between the raised backs to form an 100 upper berth, said panels being adapted to swing outwardly and meet the hinged ends of the backs to close the ends of the upper berth.

5. In a sleeping car, a central and longitudinal partition, said partition having storage spaces formed at one side of the same, panels hinged to the partition and adapted to normally close the storage spaces, seats 105 outstanding from the partition and being arranged to face one another, superposed hinged sections carried against the partition between the seats, the lower one of the sections being adapted to swing down between the horizontal portions of the seats and the 110 upper section being adapted to swing down in parallelism with and above the first section, said seats having backs adapted to swing upwardly into a horizontal plane and meet the opposite edges of the upper section, 115 said upper section being adapted to rest up against the partition to close the storage space therein.

6. In a sleeping car, a wall having storage spaces at its opposite sides, opposed seats 120 outstanding from the opposite sides of the wall, said seats having backs adapted to swing upwardly into a horizontal position,

- and hinged sections carried by the wall one above the other and adapted respectively to fill in the spaces between the horizontal portions of the seats and the ends of said backs
- 5 when the latter are raised, said upper sections when raised being adapted to close said storage spaces.

In testimony whereof I have hereunto set my hand in presence of two subscribing witnesses.

FREDERICK BRACKETT.
